PADLOCK.

1,165,545.

Specification of Letters Patent. Patented Dec. 28, 1915.

Application filed March 31, 1914. Serial No. 828,515.

To all whom it may concern:

Be it known that I, EVAN J. SHIPMAN, a citizen of the United States, residing in New Haven, county of New Haven, and 5 State of Connecticut, have invented certain new and useful Improvements in Padlocks, of which the following is a full, clear, and exact description.

This invention relates to padlocks, and 10 more particularly to padlocks provided with registering mechanism whereby the number of times that the padlock is actuated during a certain period is visually indicated on the padlock itself.

15 Padlocks of this kind are intended to facilitate the tracing of thefts.

My improvements relate more especially to registering padlocks of the pin tumbler type.

20 The primary object of the invention is to provide improved and simplified means for registering the actuations of the padlock by means actuated from the barrel or key plug of the pin tumbler lock, which is employed 25 for locking and releasing the hasp or shackle.

To this and other ends, the invention consists in the novel features and combinations of parts to be hereinafter described and 30 claimed.

In the accompanying drawing, Figure 1 is a front elevation of a padlock embodying my improvements, with the shackle closed. Fig. 2 is a similar view, with the shackle 35 open. Fig. 3 is an elevation of the lock mechanism removed from the case of the padlock, looking from the front. Figs. 4 and 5 are end views of Fig. 3. Fig. 6 is a view similar to Fig. 3, with the registering dial omitted. Fig. 6^a is a fragmentary view 40 of Fig. 6, showing the dial actuating pawl in a different position. Fig. 7 is a section on line 7—7 of Fig. 3, and Fig. 8 is a rear view of the dial detached.

45 Referring to the drawing, I have shown my improvements applied to a padlock having a case 10, and a sliding shackle 11. The padlock selected for illustration is of the general type set forth in Patent No. 729,792, 50 granted to Sargent & Company, on June 2, 1903, as assignee of Albert A. Page, and the pin tumbler lock for securing and releasing the shackle 11 comprises a case 12 carried by the face plate, or bottom plate 13, and a 55 key plug, or barrel 14 rotatable in an open-

ing in the face plate, and adapted to cooperate with the usual key 15.

The mechanism for locking and releasing the shackle is not illustrated in detail, as it is fully shown in the patent above mentioned, 60 and for the same reason it has been considered unnecessary to illustrate the means for securing the pin tumbler lock mechanism in the case 10.

In accordance with my invention, the key 65 plug 14 is adapted to actuate a pawl, or the like, each time the shackle is released, which pawl in turn actuates a registering dial having members which are successively visible through an opening in the case wall, as the 70 dial is turned on its axis. In the form shown, the case 12 of the pin tumbler lock is cut away at 16 to expose the key plug 14 and permit attachment to the key plug of a lug 17, which may be secured to the cylindrical 75 wall of the plug by means of a small screw 18. A pin 19 extending perpendicularly to the axis of the key plug, and suitably secured on the case 12 of the pin tumbler lock mechanism, serves as a pivot or fulcrum for 80 a pawl 20. This pawl is pivoted intermediate of its ends on the pin 19, and is provided with a notch 21 adapted to engage the lug 17 on the key plug, in the manner shown in Figs. 6 and 6^a, the arrangement being such 85 that when the lug 17 is moved to the right relatively to Fig. 6, the end 20^a of the pawl 20 is moved downward, whereas when the lug 17 is moved in the opposite direction, the end 20^a is returned to its elevated position, shown in Fig. 6.

The pin 19 not only serves as a pivot for the pawl 20, but also as an arbor for a registering dial 22. The rear face of the dial 22 is provided with notches or ratchet teeth 23, 95 adapted to be engaged by the end 20^a of the pawl 20, such end 20^a being suitably shaped for that purpose, as shown in Fig. 4. Hence, as the pawl is moved from the position shown in Fig. 6 to that shown in Fig. 100 6^a, the dial 22 is turned clockwise. On the return movement of the pawl 20^a, a check pawl 24 secured to the case 12, by a screw 25, engages one of the notches 23, and prevents corresponding movement of the dial 105 so that as the key plug is actuated to open the padlock a number of times, the dial 22 is rotated intermittently in a clockwise direction with reference to Fig. 3. The outer or front face of the dial 22 carries suitable 110

members adapted to be brought successively into register with an opening 26 in the front wall of the case. Supposing the parts to be in the position shown in Fig. 1, with the number 6 appearing through the opening 26 in the case, the movement of the key plug 14, incident to the release of the shackle, moves the dial 22 (by means of the pawl 20) to an extent sufficient to present the number 10. 7 at the sight opening or aperture 26. On closing the padlock, and then opening it again, the key plug will move the number 15. 8 into view. In this way, the padlock automatically registers, within certain limits, the number of times that it has been actuated, so that unauthorized actuations can be detected.

Without limiting myself to the construction shown, I claim:

20. 1. In a registering pad-lock, the combination of a shackle, pin tumbler lock mechanism for securing and releasing the same, including a key plug, a registering dial, said dial being spaced from and substantially co-extensive with the plug, and mechanism co-operating with the key plug and dial for actuating the said dial with the key plug, substantially as described.
25. 2. In a registering pad-lock, the combination of a shackle, pin tumbler lock mechanism for securing and releasing the same, including a key plug, a case inclosing said lock mechanism, a pawl pivotally mounted on said case, a member projecting from the key plug to the exterior of said case adapted to rock the pawl, and a registering dial adjacent the pawl adapted to be actuated through the medium of the pawl upon a movement of the key plug, substantially as described.
30. 3. In a registering pad-lock, the combination of a shackle, pin tumbler lock mechanism for securing and releasing the same, including a key plug, a casing for entirely inclosing said mechanism, a dial mounted on the exterior of the casing, and a second case having a sight opening through which the dial is visible adapted to inclose the same, and means for transmitting movement from the key plug to the dial, substantially as described.
35. 4. In a registering pad-lock, the combination of a shackle, pin tumbler lock mechanism for securing and releasing the same, a casing inclosing said mechanism, a registering dial mounted on the exterior of the said casing, means independent of the lock tumbler mechanism for actuating said dial upon the releasing of the lock tumbler mechanism, and a second casing having a sight opening therethrough adapted to inclose the registering dial, substantially as described.
40. 5. In a registering pad-lock, the combination of a shackle, pin tumbler lock mecha-

nism for securing and releasing the same, a casing for the mechanism, a bearing on the exterior of the case, a rocking pawl pivotally mounted on the bearing, a serrated indicating dial mounted on the bearing, and means carried by the key plug for rocking said pawl, to actuate the dial, substantially as described.

6. In a registering padlock, the combination of a shackle pin tumbler locking mechanism for securing and releasing the same, including a key plug, a casing inclosing the mechanism, and an outwardly extending bearing arranged on the exterior of the casing, an elongated rocking pawl pivotally mounted on said bearing pin, an indicator dial having a serrated portion journaled on said bearing pin adjacent the pawl and means carried by the key plug for rocking said pawl to actuate the dial substantially as described.

7. In a registering padlock, the combination of a shackle pin tumbler locking mechanism for securing and releasing the same, including a key plug, a casing inclosing the mechanism and an outwardly extending bearing pin arranged on the exterior of the case, an elongated rocking pawl pivotally mounted on said bearing pin, an indicator dial having a serrated portion journaled on said bearing pin adjacent the pawl and means carried by the key plug for locking said pawl to actuate the dial, and a second case having a sight opening therethrough adapted to inclose the dial.

8. In a registering padlock, the combination of a shackle, pin tumbler locking mechanism for securing and releasing the same, including a key plug, a casing inclosing said mechanism, a bearing pin on said casing, a pawl mounted on said pin, said pawl having a cut away portion therein, a dial adjacent the pawl and co-operating therewith, and a member carried by the key plug engaging the cut away portion in the pawl for rocking said pawl substantially as described.

9. In a registering padlock, the combination with a shackle, pin tumbler locking mechanism for securing and releasing the same, including a key plug, a casing for said mechanism and plug, a dial substantially coextensive with the casing and arranged thereon, and means for transmitting movement from the key plug to the dial, substantially as described.

10. In a registering padlock, the combination with a shackle, pin tumbler locking mechanism for securing and releasing the same, including a key plug, a rotating dial spaced from the locking mechanism, a casing having a sight opening through which said dial is visible, and means for transmitting movement from the locking mechanism to the dial, substantially as described.

11. In a registering padlock, the combina-

- tion of a shackle, locking mechanism for securing and releasing the same, a casing inclosing said mechanism, a rocking pawl on said casing, said pawl having a cut-away portion therein, a dial arranged adjacent the pawl and coöperating therewith, and a part engaging the cut-away portion adapted to rock the pawl when the shackle is released, substantially as described.
- 10 12. In a registering padlock, the combination with a shackle, a locking mechanism for securing and releasing the same, a casing for said mechanism, a rocking pawl pivotally mounted on the casing, an indicator dial journaled on the casing and coöperating with the pawl, a second casing having a sight opening therein inclosing the dial, and means for rocking said pawl to actuate the dial, substantially as described.
- 15 13. In a registering padlock the combination with a shackle, locking mechanism for securing and releasing the same, a casing for said mechanism, a registering dial jour-
- naled on the casing and spaced a slight distance therefrom, means projecting through the casing for actuating said dial upon the releasing of the locking mechanism, and a second casing having a sight opening therethrough adapted to inclose the registering dial, substantially as described.
- 20 14. In a registering padlock, the combination with a shackle, locking mechanism for securing and releasing the same, a casing for said mechanism, a rocking pawl on said casing, a dial adjacent the pawl and coöperating therewith, and a part having a loose connection with the pawl adapted to rock the same to correspondingly actuate the dial when the pawl is released, substantially as described.
- 25 30 35 40

In witness whereof, I have hereunto set my hand on the 26 day of March, 1914.
